UNITED STATES PATENT OFFICE

HANS KLENCKE, OF FRANKFORT-ON-THE-MAIN, GERMANY

DEVICE FOR ROASTING SULPHUR CONTAINING SUBSTANCES, ESPECIALLY METAL
SULPHIDES CONTAINING ORES

Application filed September 15, 1928, Serial No. 306,267, and in Germany September 13, 1927.

This invention relates to a method and a device for roasting sulphur-containing substances especially metal sulphides containing ores.

When roasting sulphur containing raw materials such as pyrite, zinc blend or the like in mechanical roasting furnaces, it is usual to let the material to be roasted drop as seldom as possible and to make the drop as low as possible from one floor to the other floor of the furnace, in order to avoid an excessive formation of dust. The removal of the sulphur from the ore took place therefore generally only on the horizontal floors of the furnace; one could however clearly notice a flaming up of the material, when it dropped from one floor to the other floor in the furnace. This flaming up was due to an accelerated combustion produced by the thorough mixture of the material with the oxygen of the air present in the furnace. It could further be noticed, that the different floors of the furnace were never equally bright, and that the combustion of the material passing across one floor was slowly decreasing during its passage and only revived by the dropping upon the next floor.

The improvement however of the dust collecting devices makes it unnecessary to work under such conditions, that the formation of dust is avoided; operations may therefore be conducted in such a manner, that dust is formed, as the dust collecting apparatus especially the electrodynamic apparatus have been so perfected, that it is absolutely immaterial, whether the furnace makes more or less dust.

Whereas formerly more than 7 or 8 floors were not used in mechanical roasting furnaces there is no trouble nowadays to increase the floors to 10 and 12. The increase in the capacity of mechanical roasting furnaces by applying more floors than before may be further raised by using fall openings on

the floors not only at the periphery and in the center of the furnace, as was hitherto the case, but also between these two places, thus providing the whole roasting surface of the floors with fall openings, which are arranged irregularly or centrally around the shaft of the furnace. By this arrangement of the fall openings the mixing of the material to be roasted with the oxygen present in the gases in the furnace is improved and furthermore a finer distribution of the ore may be obtained, than was the case formerly with the smaller amount of fall openings. In the prior construction of roasting furnaces with fall openings at the centre and at the periphery the vertically dropping stream of the material only contacted with a vertically raising gas stream, whereas according to the new arrangement it is possible to let the gas stream horizontally pass through the vertically dropping stream of the material.

The arrangement of fall openings between the usual fall openings, that is between the periphery and the centre of the floor makes it possible, for the middle part of the furnace to be fed with material having a higher sulphur content than the material which formerly passed across the whole floor. Thus the main combustion zone of the furnace is enlarged and the capacity of the furnaces may be raised.

By the use of insertion pieces of ceramic material, iron alloys or the like the size of the openings in the floors may be regulated; the insertion pieces may also be used to close some openings entirely.

In the old mechanical roasting furnaces air was introduced at the lowest floor and in about the middle of the floors. With the new mechanical roasting furnaces, having fall openings all over the floors and a greater number of floors, one may introduce air at one, two, three or more places as may be de-

sirable for obtaining a good desulphurization and a great production.

The annexed drawings show a mechanical roasting furnace according to the invention by way of example.

In the drawings,

Fig. 1 is an elevation in partial section of the furnace;

Fig. 2 is a detail in partial section of one chamber of the furnace;

Fig. 3 is a section on line 3—3 of Fig. 2, and

Fig. 4 is a horizontal section on line 4—4 of Fig. 2.

The furnace has ten floors I—X. A is the exterior wall of the furnace, B the shaft of the furnace provided with stirrers R on each of the ten floors. The ore enters the first floor of the furnace by the opening E and is slowly moved from floor to floor by the stirrers. Besides the normal fall openings F around the shaft and besides the usual fall openings G at the periphery of the floor there are arranged some additional fall openings H in several floors. Especially the floors in the middle of the furnace are provided with the greatest number of additional fall openings H. The main amount of air is introduced into the furnace in the usual manner through the hollow shaft B by a fan and by a tubing L. The additional openings L₁, L₂, L₃ may be used for adding further amounts of air.

The gases obtained by the roasting process leave the furnace at S, whereas the roasted ore leaves the furnace at N at the bottom. The shaft is driven in usual manner and the driving arrangement has therefore not been shown in the drawing.

In Figs. 2—4 is shown the manner of insertion in a part of the openings H of the pieces H' referred to above. In these figures one-half of the additional openings H are shown as closed by the pieces H'.

For roasting some ores, especially for zinc blend it may be of advantage to arrange an auxiliary heating device in the lower floors of the furnace. Thus for example one or two oil burners may be arranged in the lowest floor as shown in Fig. 2.

I claim:

1. A mechanical roasting furnace of the type comprising a plurality of floors and a rabble arm on each floor adapted to move the material to be roasted alternately from the center to the periphery and from the periphery to the center of alternate floors, wherein at least some of the floors of the furnace are provided with auxiliary openings intermediate the periphery and the center of the floors in addition to the principal openings at the center and the periphery of alternate floors, respectively.

2. In a mechanical roasting furnace of

the type comprising a plurality of floors and a rabble arm on each floor adapted to move the material to be roasted alternately from the center to the periphery and from the periphery to the center of alternate floors, a floor provided with auxiliary openings intermediate the periphery and the center of the floor in addition to the principal openings at the center and the periphery of alternate floors respectively.

In testimony whereof I affix my signature.

HANS KLENCKE.
